UNITED STATES PATENT OFFICE.

HERBERT C. KING, OF TORONTO, ONTARIO, CANADA.

PORTABLE GRAMOPHONE.

Application filed May 1, 1922. Serial No. 557,786.

To all whom it may concern:

Be it known that I, HERBERT C. KING, of the city of Toronto, in the county of York, Province of Ontario, Canada, a subject of 5 the King of Great Britain, have invented certain new and useful Improvements in Portable Gramophones, of which the following is a specification.

This invention relates to that type of 10 gramophones which when closed may be carried from place to place by the operator, and my object is to provide a gramophone which will be compact when closed, of neat appearance and cheap to manufacture.

15 I attain my objects by means of the constructions hereinafter described and illustrated in the accompanying drawings in which—

Fig. 1 is a plan view of my gramophone, 20 with the lid opened;

Fig. 2 a longitudinal vertical section of the same;

Fig. 3 a similar view to Fig. 2 showing the lid closed; and

25 Fig. 4 an end view of the same.

In the drawings like numerals of reference indicate corresponding parts in the different figures.

1 is a casing provided with a handle 15 and 30 a hinged lid 2. A motor (not shown) is suitably secured to the bottom of the casing and is adapted to rotate the turntable 3.

The common arrangement for constructing 35 amplifying chambers in portable gramophones is to close the top of the casing with a stationary cover underlying the turntable and on which the tone arm is mounted. The tone arm extends upwardly higher than the turntable so that the needle, carried by the 40 reproducer which is carried on the free end of the tone arm, may engage the spiral groove formed in the record which lies on the turntable. When the gramophone is not in use the tone arm and turntable are covered by means of a hollow lid hinged on the 45 casing. It is obvious that with this arrangement the dimensions of the gramophone, when the lid is closed, are so great that it is cumbersome and very awkward to carry.

50 I overcome the above objectionable features by constructing my gramophone so that the tone arm is swung downwardly as the lid 2 is closed thus permitting the depth of the latter to be considerably reduced.

55 This is accomplished by providing a motor

board 4 which covers the amplifying chamber and motor space and has the tone arm carrying board 4^a hinged thereon. The tone arm 5 suitably carried on the tone arm carrying board 4^a is adapted to be swung by means of the links 6, having their opposite ends pivotally connected with the movable board 4^a and the lid 2, to its operative position and to its inoperative position as the lid is opened and closed respectively. An upwardly extending hook 17 secured to the movable board 4^a is adapted to receive the free end of the tone arm. An elbow 7 secured to the underside of the movable board 4^a forms a communication between the tone arm and the amplifying chamber 8, this being preferably separated from the motor space by the curved partition 18. A transverse partition 9 forms the rear wall of this chamber and is provided with an opening through 70 which the free end of the elbow 7 projects. Abutment members 19 secured to or formed on the casing are adapted to engage the swingable board 4^a to limit its upward movement.

To regulate the volume of the reproduced sounds issuing from the amplifying chamber I provide the pivotally mounted shutters 10 which are well known in the art. To lock these shutters in their closed positions I 85 provide each end of one of the shutters with a projection 11 having an enlargement 12 formed at its outward end. The projections 11 are adapted to be received in the notches 13 formed in the latches 14 which are pivotally connected with the lid 2 and which are adapted to engage the outer surfaces of the shutters to hold the latter closed. The enlargements 12 are adapted to frictionally engage the latches 14 and tend to hold the latter in engagement with the projection 11 thus locking the shutters and the lid.

To carry a supply of records, the inside of the lid 2 is provided with an inwardly extending threaded stem 16 adapted to be 100 received in the hole formed in the records. A disk shaped nut is threaded on the stem for holding the records in place.

To reduce the cost of manufacture all the parts of the casing will be made of stamped 105 sheet metal.

What I claim as my invention is:—

1. The combination with a gramophone including a hinged lid and pivotally mounted tone regulating shutters, of means for 110

locking the lid in its closed position and adapted to engage the outer surfaces of the shutters to hold the latter closed.

2. The combination with a gramophone 5 provided with a hinged lid and pivotally mounted tone regulating shutters, of a projection extending outwardly from one of the shutters and provided with an enlargement at its outer end; and a latch pivoted on 10 the lid and provided with a notch adapted to receive the projection, the enlargement being adapted to frictionally hold the latch in its locking position.

3. In a gramophone the combination of a 15 casing provided with a turntable and an amplifying chamber located below said turntable; a tone arm carrying board hinged at its forward side at the rear end of the amplifying chamber; a tone arm carried on said

swingable board; and a forwardly curved 20 elbow secured to said board and communicating with the tone arm and the amplifying chamber.

4. In a gramophone, the combination of a 25 casing provided with an amplifying chamber including a rear wall having an opening formed therein; a motor board adapted to form a cover for the amplifying chamber; a tone arm carrying board hinged on the rear wall; a tone arm carried by the tone arm carrying board; and an elbow secured to the 30 underside of the said board and communicating with the tone arm, the free end of the elbow projecting through said opening.

Signed at Toronto, Canada, this 19th day 35 of April, 1922.

HERBERT C. KING.
